UNITED STATES PATENT OFFICE.

ERIC B. VAN NORDEN AND HENRY P. HAMBURG, OF NEW YORK, N. Y., AND SAMUEL S. HARPER, OF PHILADELPHIA, PENNSYLVANIA; ELEANOR L. HARPER EXECUTOR OF SAID SAMUEL S. HARPER, DECEASED.

PENCIL-SHARPENER.

1,121,423.

Specification of Letters Patent. Patented Dec. 15, 1914.

Application filed February 11, 1907. Serial No. 356,755.

To all whom it may concern:

Be it known that we, ERIC B. VAN NORDEN, a resident of the city of New York, county of New York, State of New York, 5 HENRY P. HAMBURG, a resident of the city of New York, in the borough of Queens, county of Queens, State of New York, and SAMUEL S. HARPER, a resident of the city of Philadelphia, in the county of Philadelphia 10 and State of Pennsylvania, all citizens of the United States, have invented certain new and useful Improvements in Pencil-Sharpener, of which the following is a full, complete, and exact disclosure.

15 The object of our invention is the production of a pencil sharpener which is simple and inexpensive in manufacture, while, at the same time, the parts may be easily assembled, which will operate with efficiency, 20 and with a minimum liability of becoming disarranged, and in which the parts which become worn or mutilated, may be easily replaced, such for instance, as the cutting blades, or knives.

25 A further object of our invention is to provide a gradual downward feed of the pencil during the sharpening operation and avoid placing the pencil under uneven lateral pressure, and this is accomplished by 30 supporting the pencil on tapering surfaces and by providing opposing knives, which, in making the cut, give substantially the same pressure on opposite sides of the pencil, or the lead carried thereby.

35 A further object of our invention is to provide a pencil sharpener with knives which may be used for a considerable length of time without sharpening, or unduly wearing the same, the same being effected, in the preferred form of our device, 40 by making the knives capable of bringing a new cutting edge into engagement with the pencil after every cut.

45 A further object of our invention is to provide an article which may be conveniently placed upon a desk where it is accessible whenever it is desired to sharpen a pencil, which is of such a shape that it may be used for other purposes, as for instance, 50 a paper weight, and which will provide a receptacle for the chips removed in sharpening the pencil, or for pens, pins, paper fasteners, and other similar accessories.

Further objects of our invention will appear in the specification and claims below. 55

Briefly, our invention comprises a knife, or plurality of knives, or blades, which are guided in such a manner as to shave or cut the end of the pencil at the point to be sharpened without further operation by the 60 user, than the simple reciprocation of a suitable slide mounted on the outside of a suitable casing. This movement will cause the cuts to be evenly and accurately made at the end of the pencil, while the shavings, or 65 chips, which are removed therefrom, are prevented from becoming scattered, thus obviating all danger of injuring the hands of the person using the sharpener, or littering the desk, or soiling the papers which may 70 be thereon.

For a full, clear and detailed description of one form of our invention, reference may be had to the following specification, and to the drawings forming a part thereof, in 75 which—

Figure 1 represents a perspective view of our improved pencil sharpener; Fig. 2 is a vertical sectional view showing the knives at their lowest position, or at the end of a 80 cutting stroke; Fig. 3 is a similar sectional view showing the knives in their raised positions, or at the beginning of the cutting stroke; Figs. 4 and 5 are obverse and reverse views respectively of the cutting 85 knives and their carriers; Fig. 6 is a detail view of the mechanism for lifting and rotating the pencil during the operation of the device; Figs. 7 and 8 are perspective views of the pencil guides; Fig. 9 is a detail 90 view showing a pencil and its relation to said guides and Fig. 10 is a detail view of the ratchet for rotating the blades.

Referring to the drawings, 1 indicates a suitable base, or standard which is preferably heavy, and to the upper surface of which is attached a shallow dish 2, which may serve as a tray which will receive the shavings and particles of lead which are removed from the pencil. 95

3 indicates a suitable casing, the bottom 4 of which is secured to the top of the tray by means of a screw 5. This casing may be of any suitable shape in cross section, but it should be provided with a pair of flat parallel sides 3', each of which is provided with 100

105

a pair of converging slots or guide ways, 6, 6', for the knife carriers, which are to be described below. The vertical sides of the casing should be parallel to form a guiding surface for the ring, or band, 7 which constitutes the means which is grasped between the fingers of the operator for operating the mechanism. One of the slots, as for instance 6 on each side of the casing 3, is provided at its upward end with an enlarged hole, or opening 8 through which the cutting knives are inserted within, or removed from the casing.

Referring now particularly to Figs. 4 and 5, the knives 9, consist of a carrier 10, having flat parallel opposite sides 11, 11, adapted to fit within the contracted portions of the slots 6—6'. At the central portion of the carrier on studs 12, are mounted circular blades 13 and between the blades and the carrier, and rigidly secured to the back of each blade, is a ratchet 14 having a comparatively large number of very fine teeth. On the outside of each of the blades, and also secured to the studs 12 are heads 15 adapted to support and steady the said blades 13.

The outer parallel ends of the guiding surface of the carriers project through the slots 6, 6', and when in operative position, their upper ends rest against the inwardly turned top sides 7' of the band 7. The ends of the carriers are retained within the band by said sides 7' and the pins 16 passing through openings 17 in said band, and having their ends bent at substantially right angles so that when the said ends are turned into the position shown in Fig. 1 to rest within grooves 18 in the outside of the carrier, the pins are locked to the said band. The ends of the blades then are held in position with respect to the band 7 by the in-turned tops 7' and the pins 16. Adjacent the upper end of each slot 6' is a pawl 19, pivoted to a bracket 20, and retained in a substantially horizontal position by a lug 21, resting against a stud 22 of said bracket.

By means of the mechanism above described, a reciprocation of the band 7 will cause the knives 9 to traverse the slots 6, 6' in the casing, and when the knives are near the upper end of their travel, the ratchets 14 will come into engagement with the pawls 19 and the blades 13 will be given a short movement of rotation. As the ratchets contain a large number of teeth, and as the amount of rotation of the blades will depend upon the point to which the band 7 is lifted, it will take a large number of reciprocations of the band 7 to bring the same point in the circumference of the circular blades into operative cutting position with respect to the pencil, with the result that at every reciprocation of the band 7, a new point of the circumference of the cutting blades 13 is caused

to engage the pencil. The blades will, therefore, be prevented from becoming nicked or worn in any one particular spot, and will consequently last, or remain sharp for an indefinite length of time.

The pencil holder consists of the circular tube 23 having one or both of its ends split longitudinally as at 24, to form spring fingers 25, which tightly clasp the pencil, and to the body portion of the said tube 23 is secured a sleeve 26, the upper end of which is provided with a ratchet 27 having downwardly extending teeth 28. The upper end of the said ratchet 27 is provided with an inwardly extending flange 29, which loosely surrounds the tubular sleeve 30, struck inwardly from the top of the casing and provided at its lower end with a flange 31. Also secured to the top of the casing by struck up lugs 32, passing through suitable openings 32' and fitted within the inside of the casing, are two complementary members 33—33, which together form a head 34, provided with a ratchet 35 coöoperating with the ratchet 28 and a downwardly extending tubular portion 36 which terminates in a conical pencil supporting surface 37. The sides of the conical pencil supporting surface are cut away and bent backwardly as at 38 to form an opening 39 to permit the blades 13 to engage with the outer side of the pencil. The lower ends of the said members extend through the top of the partitions 40, fitted within the lower end of the casing, and are bent sidewise, as at 33', against said partition, thereby locking said members and said partitions together.

41 indicates the flat top of the partition 40, upon which the lead of the pencil rests when the sharpening of the same has been completed.

42 indicates a coiled compression spring having its ends resting upon the top of the ratchet 26, and the inside of the top of the casing respectively and acting to normally hold the ratchet teeth 28 in engagement with the ratchet teeth 35.

43 indicates a pivoted member carrying at the top thereof a pawl 44 adapted to pass through the slot 45 in the head 34 of the member 33, and coöoperating with the ratchet teeth 28 of the ratchet 27. This member is pivoted to the inside of the casing as at 46 and is provided with two arms 47 and 48, which extend outwardly and are adapted to swing into the path of the carriers 10.

The operation of our device is as follows: The parts being in the positions indicated in Fig. 2, a pencil is inserted within the spring fingers 24 until its lower end rests upon the pencil supporting surface 37. The band 7 is then lifted upward and the knives are raised to the position shown in Fig. 3. The upward movement of the knives brings

the carrier 10 into contact with the arm 47 which turns the member 43 about its pivot 46 carrying the pawl 44 upwardly into engagement with the ratchet teeth 28, the effect of which is to lift the ratchet 27, the pencil holder, and the pencil carried thereby for a short distance and to give the same a partial rotation about the axis of the pencil. The band 7 is then moved downwardly, which movement allows the ratchet 26 to come into contact with the ratchet teeth 35 and to prevent any backward rotation of the pencil. The knives continuing to descend, cut or shave off the opposite sides of the pencil through the opening 39, and the chips drop on the partition 40 and pass downwardly through the opening 49 in the side of the casing to the tray 2. In moving downwardly, the carrier engages the arm 48 of the member 43 and returns the pawl into the position shown in Fig. 2 into position to engage another tooth 28 of the ratchet 27. The next upward movement of the knives lifts the pencil carrier 24 and gives it another short movement, or rotation and the operation is repeated.

As above stated, the pawl 19 which engages with the ratchet 14 of the rotating knives, serves to provide a new cutting surface for each reciprocation of the knives.

By providing a structure in which the pencil is lifted from the tapered pencil supporting surface 37 at the end of each cut, the pencil may be easily rotated to bring a new portion of the pencil into alignment with the paths of the knives without being obliged to overcome any friction between the said surface and the pencil point during the rotation.

The downward feed of the pencil is accomplished in the following manner: After the blades 13 have taken a cut from the pencil they are returned to their highest position and in doing so the knife carrier 10 comes in contact with the arm 47 of the pivoted member 43, thus giving the pencil a partial rotation about its axis and presenting a new portion of the same to the action of the cutting blades, so that when the knives again descend and engage the pencil to cut another chip, the pencil is drawn downwardly firmly into the conical pencil supporting surface 37 until there is sufficient resistance to cause the knives to cut. This operation is repeated and as the pencil is cut away, it is automatically fed downwardly until the point of the sharpened pencil rests upon the top 41 of the partition 40, whereupon the knives having taken a final cut around the pencil, will cease to cut, thus indicating that the sharpening operation has been completed. In this way it is not possible to cut away and waste the pencil, while the pencil is always pointed or sharpened in the same manner and the lead

of the pencil is always of the same length as it was before the pencil was sharpened. It will thus be seen that the pencil is not unnecessarily cut away, and the life of the pencil is, therefore, greatly prolonged.

We have found it is preferable to make the angle formed by the guides 6 and 6' for the knives more acute than the angle of the taper of the pencil supporting surface. This feature is clearly illustrated in Fig. 9 of the drawings, in which it will be noted that the taper of the pencil is sharper than the taper of the supporting surface, the angle which the knife makes with the pencil corresponding to the taper of the pencil. With this construction, the guides or supporting surface diverging upwardly at a wider angle than the angle which the knife makes with the pencil, lets the knife down deeper than it would if the angles of the two were alike, and as the knives come down they cut off a comparatively heavy chip, but as the pencil is cut away and fed down, the angle of the guiding or supporting surfaces converge or come together more rapidly than the angle to which the pencil is cut, so that after one sheet has been removed, the pencil is allowed to feed downwardly a little less distance than it was at the preceding cut of the knives, and when the pencil reaches the bottom and can go no farther, no chip is removed from the pencil. Thus it is that a smaller and smaller chip is removed from the pencil as the pencil is allowed to feed downwardly. This construction provides for a graduated downward feed of the pencil through the cutting operation, the knives are not required to remove so heavy a chip when finishing the sharpening operation as at the beginning of the same, and the liability of breaking the lead is greatly reduced.

In connection with the description of the parts and the operation thereof with respect to each other, it will be apparent that the casing or standard 3 and the ring or band 7 are parts which have a relatively slidable movement with respect to each other, and that by reason of the slots longitudinal of the casing 3 and arranged at an angle with respect to the axis of the pencil through which the ends of the carrier for the knives extend, together with the inturned edges 7' of the band 7, and the pins 16 adjacent the lower edge of the band, give to the knives, when one of said members is moved with respect to the other, both a longitudinal and a transverse movement. The recess in the band 7 between the inturned edge 7' and the pin 16 constitutes substantially a transverse slot or groove in the band or ring 7, which permits of the transverse motion of the knives. These parts, therefore, form a co-operative means for operatively locating or determining the position of the knives within the casing 3, and for giving to the knives

a transverse and longitudinal movement, whereby the knives are moved progressively toward the axis of the pencil on the downward stroke and away from the axis of the pencil on the upward stroke thereof.

Having thus described our invention, what we claim as new and desire to protect by Letters Patent of the United States is:

1. In a pencil sharpener, the combination 10 with a cutting knife with coöperating means for operatively locating said knife in said sharpener, comprising relatively movable parts, said parts respectively having angularly disposed guides for giving said knife 15 a transverse and longitudinal movement in relation to the pencil to be sharpened.

2. In a pencil sharpener, the combination 20 with a rotatable cutting knife, of coöperating means for operatively locating said knife in said sharpener, comprising relatively 25 slidable parts respectively having guides disposed at angles for giving said knife a longitudinal and transverse movement in relation to the pencil to be sharpened.

3. In a pencil sharpener, the combination 30 with a cutting knife, of coöperating means for operatively locating said knife in said sharpener, comprising relatively slidable parts, one of said parts having longitudinal 35 slots and the other of said parts having grooves disposed transversely to said slots for giving said knife a longitudinal and transverse movement in relation to the pencil to be sharpened when one of said parts is reciprocated.

4. In a pencil sharpener, the combination 40 with a plurality of opposed cutting knives, of coöperating means for operatively locating said knives in said sharpener, said means having respectively longitudinal and transverse guides for giving said knives converging movements when reciprocated in relation to the pencil to be sharpened.

45 5. In a pencil sharpener, the combination with a plurality of opposed cutting knives, of coöperating means for operatively locating said knives in said sharpener, said means having respectively longitudinal converging 50 guides and transverse guides for giving said knives converging movements when reciprocated in relation to the pencil to be sharpened.

55 6. In a pencil sharpener, the combination with a plurality of opposed cutting knives, of coöperating means for locating said knives within said sharpener, and for giving the same a longitudinal and transverse movement in relation to the pencil to be sharpened 60 when the parts of said means are operated.

7. In a pencil sharpener, the combination with a plurality of opposed cutting knives, of means for giving said knives a longitudinal movement in relation to the pencil and

a support having converging slots within 65 which said knives are adapted to work and which give a transverse movement to the knives in relation to the pencil to be sharpened.

8. In a pencil sharpener, the combination 70 of a plurality of opposed cutting knives, a frame engaging said knives for giving the same a longitudinal movement in relation to the pencil to be sharpened, and a casing having converging slots therein for giving 75 said knives a transverse movement in relation to said casing.

9. In a pencil sharpener, the combination 80 of a support having a central socket therein, a casing carried by said support, having converging slots therein, cutting knives engaging said slots, and a slidable frame also engaging said knives, for giving the same a longitudinal movement in relation to said casing. 85

10. In a pencil sharpener, the combination 90 of a support having a tapering socket, therein, and having converging cut away portions intersecting said socket, a casing inclosing said support and having converging slots 95 therein corresponding to the cut away portions of said support, knives engaging said slots, and a frame also engaging said knives, and slidable upon said casing, for giving said knives a longitudinal movement within 95 said casing.

11. In a pencil sharpener, the combination 100 of a support having a tapering socket therein, and having converging cut away portions, a casing having converging slots. 100 knives engaging said slots and a flanged frame which also engages said knives and by which a longitudinal movement may be given thereto.

12. In a pencil sharpener, the combination 105 of a support having a socket therein, and having converging cut away portions intersecting said socket, a casing having converging slots therein, knives engaging said slots, said knives having off set cutting edges to 110 bring them adjacent the surface of the cut away portions and means for giving said knives a longitudinal movement in said slots.

13. In a pencil sharpener, the combination 115 with a rotatable cutting knife, of coöperating means for operatively locating said knife in said sharpener, the same comprising relatively slidable parts respectively, having guides disposed at angles to each other for giving said knife a longitudinal and transverse movement in relation to the pencil to be sharpened and means for turning said knife. 120

14. In a pencil sharpener, the combination 125 with a plurality of opposed rotatable cutting knives, of coöperating means for giving the same reciprocating movements in converging paths, and means for automatically ro-

tating said knives as they approach one end of their longitudinal movement.

15. In a pencil sharpener, the combination of a plurality of opposed knives, coöperating means for imparting a converging motion to said knives toward the sharpened end of said pencil, and means engaged by said knives for imparting a motion to said knives for bringing different cutting edges of said 10 knives successively into operative relation with said pencil.

16. In a pencil sharpener, the combination of a plurality of opposed rotatable knives, coöperating means for giving said knives a 15 converging longitudinal motion in a direction toward the point of the pencil, means for automatically rotating said knives while the same are out of contact with said pencil and as they approach one end of their longitudinal movement.

17. In a pencil sharpener, the combination of a plurality of opposed rotatable knives, coöperating means for reciprocating said knives in paths converging toward the point 25 of said pencil and means for automatically rotating the said knives while the same are out of engagement with said pencil and as they approach the end of their longitudinal movement.

30 18. In a pencil sharpener, the combination with a pair of opposed knives, of coöperating means for reciprocating said knives in paths converging toward the point of the pencil, a pencil holder, and means for lifting said holder and for rotating the same with respect to said knives.

19. In a pencil sharpener, the combination with a pencil holder and a pencil support, of a plurality of knives adapted to engage a 40 pencil in said support, coöperating means for advancing said knives in paths converging toward the point of the pencil on the cutting stroke, and means for lifting said holder away from said support on the return stroke.

20. In a pencil sharpener, the combination with a pencil holder and a pencil support, of a plurality of knives adapted to engage a pencil, coöperating means for advancing said knives in paths converging toward the point of the pencil on the cutting stroke, and means for lifting the pencil out of engagement with said support and for rotating the same on the return stroke of said knives.

55 21. In a pencil sharpener, the combination with a cutting knife and means for reciprocating same, of means operative to revolve a pencil, and automatic means for causing the knife to remove a progressively lighter chip from the pencil after each revolution of said pencil.

60 22. In a pencil sharpener, the combination with a knife mounted to reciprocate in a fixed plane, of a support for a pencil, and

automatic means for causing the knife to 65 remove a progressively lighter chip from the pencil by gradually decreasing steps during the operation.

23. In a pencil sharpener, the combination with a knife mounted to reciprocate in a 70 fixed plane, of a fixed support for the end of the pencil and automatic means for causing the movement of the end of the pencil into the cutting path of the knife by gradually decreasing distances, the point of the 75 pencil being held against further advancement toward the cutting plane when the sharpening operation is completed.

24. In a pencil sharpener, the combination with a plurality of opposed cutting 80 knives and means for giving said knives longitudinal movement in relation to the pencil, of a pencil support having an internal conical surface for supporting said pencil, the angle of which is greater than the angle 85 of the point of the pencil when sharpened.

25. In a pencil sharpener, the combination with plurality of opposed knives and coöperating means to reciprocate said knives in paths slanting toward the end of 90 the pencil, of a pencil support having an internal conical surface for supporting said pencil during the sharpening operation, the taper of said surface being greater than that formed by the paths in which said knives 95 reciprocate.

26. In a pencil sharpener, the combination with a pencil holder, movably mounted, of a knife, means to reciprocate said knife substantially longitudinally with respect to 100 said holder, and means actuated by said first mentioned means for moving said holder longitudinally and for rotating the same.

27. In a pencil sharpener, the combination with a pencil holder yieldingly mounted, of a knife mounted to reciprocate with respect to said holder, means for automatically rotating said knife, and means moving said holder longitudinally, as the said knife approaches one end of its reciprocation. 110

28. In a pencil sharpener, the combination with a pencil holder yieldingly mounted, of a fixed support for the end of the pencil, a knife, means to reciprocate said knife, and means actuated by said means for reciprocating said knife for moving said holder longitudinally and for rotating the same. 115

29. In a pencil sharpener, the combination with a tray and a vertical casing supported thereon, of a support for the pencil 120 within said casing, said casing being provided with openings in the sides thereof adjacent the bottom of the casing, and with inclined surfaces leading from beneath said pencil holder downwardly to said openings 125 whereby chips from the pencil are carried through the openings and into the said tray.

30. In a pencil sharpener, the combina-

tion with a fixed hollow support adapted to receive the end of a pencil, of a rotatable yieldingly mounted holder for said pencil, coaxial with said support, a knife, means to reciprocate said knife, and means actuated by said means for reciprocating said knife for moving said holder longitudinally and for rotating the same.

31. In a pencil sharpener, the combination with a casing, of a head within said casing, said head being secured at one end adjacent one end of said casing and converging toward the other end of said casing and terminating in a conical support for the pencil point, the interior of said head being provided with an annular shoulder, a tubular pencil holder arranged within said head and concentric therewith, said casing being provided with an aperture concentric with said holder, an annular flange secured to said holder concentric therewith within said casing, said flange being adapted to rest upon said annular shoulder, and said flange being provided upon the surface against said shoulder with a ratchet, a spring to hold said flange yieldingly in contact with said shoulder, a knife mounted to reciprocate to sharpen the pencil, and a pawl engaging with said ratchet and actuated by the movement of said knife to move longitudinally and to rotate said holder.

32. In a pencil sharpener, means for holding a pencil, a pair of knives located on opposite sides of the axis of the pencil and means to cause said knives to reciprocate in substantially right lines converging toward the point of the pencil to take substantially equal cuts simultaneously on opposite sides of the pencil.

40 33. In a pencil sharpener, means to hold a pencil, a pair of rotatable knives mounted on opposite sides of the axis of the pencil, means to move said knives in paths converging toward the point of the pencil to cause said knives to take substantially equal cuts simultaneously on opposite sides of the pencil, means to retract said knives away from the point of the pencil, and means to rotate said knives as they recede from the point of the pencil.

45 34. In a pencil sharpener, the combination with a pencil holder, movably mounted, of a knife, means to move said knife to and fro substantially longitudinally with respect to said holder, and means actuated by said first mentioned means for moving said

holder longitudinally and for rotating the same.

35. In a pencil sharpener, the combination with a pencil holder yieldingly mounted, of a fixed support for the end of the pencil, a knife, means to move said knife to and fro, and means actuated by said knife moving means for moving said holder longitudinally and for rotating the same. 60

65 36. In a pencil sharpener, the combination with a fixed hollow support adapted to receive the end of a pencil, of a rotatable yieldingly mounted holder for said pencil, coaxial with said support, a knife, means to move said knife to and fro, and means actuated by said knife moving means for moving said holder longitudinally and for rotating the same. 70

75 37. A pencil sharpener comprising a pencil supporting structure, a knife mounted thereon and movable to and fro, a pencil holding sleeve, pawl and ratchet mechanism operable by the movement of said knife in one direction to simultaneously move said pencil holding sleeve rearwardly and to revolve it, and means for moving said sleeve forward after the turning thereof.

80 38. A pencil sharpener comprising a supporting structure, a pencil holder fixed thereto, a clamping sleeve slidably engaged with said holder, a knife mounted on said holder and movable to and fro, and cooperating elements carried by said knife and sleeve and operable by the rearward movement of said knife to simultaneously move the pencil sleeve longitudinally and rearwardly and to revolve it. 85
